(57) **CLAIM**

The ornamental design for an orthopedic boot, as shown and described.

DESCRIPTION

FIG. 1 is a front view of the orthopedic boot, showing my ornamental design;

FIG. 2 is a back view thereof;

FIG. 3 is a left side view thereof;

FIG. 4 is a right side view thereof;

FIG. 5 is a top plan view thereof; and,

FIG. 6 is a bottom plan view thereof.

It is understood that the broken lines within the claimed design indicate stitch lines, which form part of the claimed design.

1 Claim, 6 Drawing Sheets

FIG. 2

FIG. 3

FIG. 4

FIG. 5

FIG. 6
